AQUARIUM STAND

Richard S. Young, Frankenmuth, and Leo E. Hearn,
Flint, Mich., assignors to Pentaco Enterprises Corporation,
Chesaning, Mich.

Filed June 12, 1972, Ser. No. 261,904

Term of patent 14 years

Int. Cl. D30—02; D06—03

U.S. Cl. D30—12

FIG.4

FIG. 1 is a perspective view of an aquarium stand, showing our new design;

FIG. 2 is a side elevational view, the opposite side being substantially a mirror image thereof;

FIG. 3 is a side elevational taken at an angle of sixty degrees from FIG. 2 around a vertical axis, the opposite side being substantially a mirror image thereof;

FIG. 4 is a top plan view; and

FIG. 5 is a bottom plan view thereof.

We claim:

The ornamental design for an aquarium stand, substantially as shown and described.
